UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

TURBINE.

No. 924,546.

Specification of Letters Patent.

Patented June 8, 1909.

Application filed February 24, 1902. Serial No. 95,170.

To all whom it may concern:

Be it known that I, WILLIAM LE ROY EMMET, a citizen of the United States, residing at Schenectady, in the county of Schenectady, State of New York, have invented certain new and useful Improvements in Turbines, of which the following is a specification.

Elastic fluid turbines as commonly constructed are provided with one or more sets of rotary vanes or buckets arranged on the periphery of a wheel or cylinder, and between the rotary vanes, when more than one set is used, are other vanes or buckets which receive the motive fluid from one set of moving vanes and direct it into a second set, this action being repeated for each set of moving and stationary vanes. The vanes or buckets of the moving element may be cut from the solid stock or may be made detachable; in either event it is desirable to provide means for covering or closing in the ends of the buckets in order to form fluid passages of definite and predetermined cross-sectional area and to reduce losses by leakage. The same closing in of the ends is desirable on the stationary vanes or buckets and for the same reasons.

Previous to my invention all turbines of the above described class with which I am familiar were provided with covers made of continuous steel rings shrunk or pressed on over the ends of the vanes of the revolving element and retained in place by screws. Such a cover is expensive and inconvenient to machine, and with the speeds ordinarily used the strain on the holding devices due to centrifugal action is excessive. Owing to the construction of the parts it is often not practicable to make each one of these attachments strong, and consequently the cover is liable to be a source of danger and a limitation upon the safe design of a machine.

My invention has for its object to overcome the objections above pointed out, and the novel features will be more fully set forth in the description and in the claims appended thereto.

In the accompanying drawing, which illustrates an embodiment of my invention, Figure 1 is a perspective view of a part of a turbine-wheel; Fig. 2 is a side elevation of a wheel; Fig. 3 is a side elevation of one of the sets of stationary vanes; Fig. 4 is a plan view of a portion of one of the cover sections; and

Fig. 5 is a plan view of a slight modification.

1 represents the wheel blank before the vanes or baskets are cut; and it will be seen that an annular projection 2 is provided having a groove 3. This arrangement leaves two smaller annular projections 4 and 5 which are afterward cut to shape and riveted over the sections of the cover. The periphery of the wheel blank is turned true and may be slightly larger in diameter on one side than the other; this is done to provide the passage space 6 with the necessary area to provide for expansion or decrease of velocity in the motive fluid as it passes from one side of the wheel to the other. The same thing could be accomplished by forming the periphery of the blank so that it extended parallel with the axial line, but it would involve cutting the vanes longer on one side than on the other, which is a difficult and expensive operation, however the vanes are made. The feature of making the wheel blank slightly larger in diameter on one side than on the other further increases the cost and difficulty of making a continuous ring cover as heretofore constructed. The vanes 7 are preferably made integral with the stock forming the wheel blank, but detachable vanes may be used and certain of the benefits of my invention will still follow. The passages 6 may be given any suitable shape, and at the time the stock of the blank is cut away to form them, tenons or projections 8 are also formed out of the annular projection 2. The tenons, formed integral with the vanes, extend at right angles to the plane of the ends thereof, and the subdivision of the small annular projections 4 and 5 furnishes the requisite amount of stock for riveting purposes. The tenons and passages being formed by the same operations, the cost of construction is reduced to a minimum.

The cover 9 is made discontinuous or jointed and preferably in sections, each section being provided with straight ends and a plurality of openings to receive the tenons 8 on the vanes. The ends of each section are provided with notches or slots of sufficient size to receive one half of a tenon, the remainder of said tenon being surrounded by the adjacent cover section. The tenons, being cut at the time the vane is formed and by the same tool, partake, to a certain extent, of the curvature of the vane, and consequently the openings in the cover sections

are provided with two straight sides 10 corresponding to the sides of the tenons, and two curved portions 11 corresponding to the front and back of the vanes. In order to 5 decrease the liability of the advancing end of a cover section from projecting outwardly beyond the rear end of the preceding section and striking against some stationary object within the wheel casing, the said end may be 10 beveled, rounded or cut away as is indicated at 12. The sections of the cover are made from sheet steel and the openings therein are punched with the ordinary punch and die. By this means all hand work on the cover is 15 obviated. The several sections are given the proper curvature by a suitable bending device in order that they may closely conform to the periphery of the wheel. After the sections are mounted in place the edges of 20 the tenons are riveted over by suitable tools, such for example, as a pneumatic hammer and a set. By making the ends of the cover section straight instead of notched one section can be applied to or removed from the 25 wheel without disturbing the other section or sections. After mounting the cover in place on the wheel, the said cover may be turned in a lathe or other machine to render the edges true.

30 The vanes or buckets radiate from a common center, and in order to apply the detachable cover sections thereto, the pitch of the openings must be equal to the pitch of the vanes or buckets at their ends. This 35 means that there will be a slight clearance between the tenons and the ends of the slots when the section is seated. The sides of the tenons are arranged to make a close fit with the sides of the opening at all times.

40 At the time the ends of the tenons are riveted over, the clearance space above referred to is closed against the escape of steam. It is desirable to give each cover section a slightly greater curve than is demanded by the curvature of the vanes so that 45 when riveted in place the ends of the adjacent sections are in firm contact and make a steam-tight joint.

50 The construction described presents many advantages in the way of reduced cost, since the cover can be made relatively thin to reduce the dead weight yet at the same time be firmly secured in place, thereby greatly reducing the dangers due to centrifugal action.

55 Another advantage of the construction described resides in the fact that there is no rim tension. The strain on the cover is due solely to centrifugal action. Any tendency of the cover to expand in the plane of the 60 wheel causes it to more closely grip the tenons on the buckets.

My invention is directed principally toward the construction of the revolving elements of turbines, but certain advantages in

the way of reduced cost of construction may 65 accrue when used on stationary vanes. Such a construction is illustrated in Fig. 3, wherein 13 represents the curved stationary element of a turbine having a plurality of vanes or buckets 14 which receive fluid from 70 one vane-wheel, change the direction thereof and deliver it to a second vane or bucket-wheel. Each of the vanes is provided with a tenon 15 which passes through a corresponding opening in the cover section 16 and 75 is riveted over at the end to hold the section in place. In certain instances I may use the same kind of sections for both the revolving and stationary elements, or the sections may vary somewhat as to dimensions, etc., but 80 the same general principle of construction can be followed in both cases. Under ordinary conditions the cover sections would not be removed from the wheel or from the stationary element after being mounted in 85 place, but it can be done by forcing the metal forming the tenon back away from the opening in the section by a suitable tool, and this without affecting the other sections.

In Fig. 5 the sections of the cover are 90 made somewhat smaller, each section being equal in length to the pitch of the vanes or blades. The ends of the sections are made straight so as to form a good joint with the adjacent sections. In the ends of the sections are notches or slots arranged to receive 95 portions of the tenons. In the present instance each notch is capable of receiving one half of a tenon. When the ends of the tenons are riveted over, each tenon will assist in 100 holding the ends of two adjacent cover sections. This same principle is followed in the previous figures, the only difference being that there are fewer sections for a given number of vanes or blades, and hence the 105 number of tenons which engage with two sections is decreased.

One vane or bucket 7 is shown in dotted lines with the tenon 8 projecting above the cover, the slight clearance space previously 110 referred to being indicated at 17. The space is somewhat exaggerated in the figure in order that it may be seen; in actual practice I make it as small as possible.

I may, without departing from the spirit 115 of my invention, omit the tenon on one or more of the vanes or buckets under each cover section, in which case an additional amount of machining is required. In my opinion this is not such a desirable construction for the average turbine element, but in 120 special cases it may be found to be useful.

In accordance with the provisions of the patent statutes, I have described the principle of operation of my invention, together 125 with the apparatus which I now consider to represent the best embodiment thereof; but I desire to have it understood that the ap-

paratus shown is only illustrative, and that the invention may be carried out in other ways.

What I claim as new and desire to secure by Letters Patent of the United States, is—

1. In a turbine, the combination of a plurality of vanes, a sectional covering for the ends of the vanes, notches in the sections of the covering and means for securing the sections in place.

2. In a turbine, the combination of a plurality of vanes, a sectional covering for the ends of the vanes, and means formed integral with the vanes for securing the sections in place.

3. In a turbine, the combination of a plurality of vanes, a sectional covering for the ends of the vanes, each section being provided with a plurality of openings registering with the vanes, and tenons which pass through the openings and are riveted over to hold the sections in place.

4. In a turbine, the combination of a plurality of vanes, tenons formed thereon, with a sectional covering for the ends of the vanes, each section being provided with notches or slots at the ends and arranged to partially surround the tenons and be held in place thereby.

5. A cover for closing in the ends of turbine vanes, composed of a plurality of sections, each section having a cut-away or beveled end.

6. A cover for the revolving member of a turbine, composed of a plurality of sections, each section having more than two openings formed therein and provided with a beveled or cut-away end.

7. In combination, a turbine wheel, vanes or buckets formed integral therewith, tenons on the vanes, and a detachable cover composed of sections, each section being provided with end notches or slots and arranged to partially surround the adjacent tenons, and openings formed intermediate the ends through which the intermediate tenons project.

8. In a turbine, the combination of a plurality of vanes or buckets, a detachable cover for the vanes or buckets which is composed of sections, each section being provided with straight ends so that it can be applied to or removed from the vane or bucket structure without disturbing the other section or sections, and means for retaining the independent sections in place.

9. As an article of manufacture, a section of a cover for the ends of turbine vanes or buckets, comprising a sheet or strip of metal having notches or slots at the ends and two or more openings between the ends, the said openings having parallel sides and curved ends.

10. As an article of manufacture, a turbine element comprising a body portion

having a plurality of vanes or buckets radiating from a common center, tenons formed integral therewith and a jointed cover which is secured in place by the tenons.

11. As an article of manufacture, a turbine element comprising a body portion having a plurality of radial vanes or buckets formed integral therewith, each vane or bucket being provided with an integrally formed tenon and a jointed detachable cover having notches formed therein registering with the tenons.

12. As an article of manufacture, a sectional cover for a turbine element comprising a sheet or strip of metal having notches or slots formed in the ends for receiving the attaching means.

13. As an article of manufacture, a turbine element comprising a number of vanes or buckets, each vane or bucket being provided with a tenon having side faces extending parallel with the sides of said element, and other faces which follow the contour of the vanes or buckets for a portion of their length.

14. In combination, a turbine element having a plurality of vanes or buckets, a cover therefor composed of a number of sections, each section having an end notch or slot, and tenons formed on the vanes which extend through the notches or slots and are riveted over or expanded at the ends to retain an end of each section in place.

15. In combination, a turbine element having a plurality of vanes or buckets, a cover therefor composed of a number of sections each section being provided with openings and straight ends, and curved on a different radius than the element to which it is applied, and means which extend through the openings for retaining the sections in place.

16. As an article of manufacture, a cover for turbine vanes or buckets, comprising a sheet or strip of metal having an end notch or slot, and one or more openings between the ends.

17. As an article of manufacture, a section of a cover for turbine vanes or buckets, comprising a sheet or strip of metal having one or more notches or slots, and one or more openings between the ends.

18. As an article of manufacture, a cover for turbine vanes or buckets, comprising a sheet or strip of metal having notches or slots at both ends, and one or more openings between the ends.

19. A turbine comprising vanes or buckets having projections, in combination with a cover having an end notch and one or more openings, the said notch and openings registering with the projections.

20. A turbine comprising a plurality of vanes or buckets formed integral with their support, in combination with tenons forming

an integral part of the buckets and support, and a cover which is provided with openings registering with the tenons and held in place thereby.

5 21. In a turbine, the combination of vanes or buckets having curved front and rear faces, tenons formed on the buckets, having two flat surfaces and two surfaces which partake of the curvature of the buckets, and a 10 cover having openings therein, which register with and correspond in shape to the tenons.

22. As an article of manufacture, a cover for the ends of turbine blades or buckets, comprising a sheet or strip of metal having 15 notches or slots at the ends, and two or more openings between the ends, the said openings having parallel sides and curved ends.

23. In an axial-flow turbine, the combination of a support, a plurality of radiating 20 vanes carried thereby, tenons formed integral with the vanes and projecting from their outer ends, and a cover confining the steam to the bucket spaces applied to the free ends of the vanes and provided with openings to 25 receive the tenons and through which the latter extend, such cover transmitting its centrifugal strains radially to the support through the vanes.

24. In a turbine, the combination of a support, a plurality of vanes or buckets carried thereby, and a cover confining the steam to the bucket spaces secured to the free ends of the vanes or buckets and made up of sections.

25. In an axial-flow turbine, the combination of a support, a plurality of radiating 35 vanes or buckets carried thereby, and a cover confining the steam to the bucket spaces secured to the free ends of the vanes or buckets and divided into sections.

40 26. In an axial-flow turbine the combination of a support, a plurality of radiating vanes or buckets carried thereby, and a cover confining the steam to the bucket spaces secured to the free ends of the vanes or buckets 45 by the interlocking of integral parts of the two elements, such cover transmitting its

centrifugal strains to the support through said vanes or buckets and interlocking parts.

27. In an axial-flow turbine, the combination of a support, a plurality of radiating 50 vanes or buckets carried thereby, and a cover confining the steam to the bucket spaces secured to the free ends of the vanes or buckets by riveting an integral part of one element upon the other, such cover transmitting its 55 centrifugal strains radially to the support through the vanes or buckets.

28. In an axial-flow turbine, the combination of a support, a plurality of radiating 60 vanes or buckets carried thereby, and a jointed cover confining the steam to the bucket spaces riveted to the free ends of the vanes or buckets.

29. In an axial-flow turbine, the combination of a support, a plurality of radiating 65 vanes or buckets carried thereby, and a jointed cover secured to the free ends of the vanes or buckets by riveting an integral part of one element upon the other.

30. A turbine bucket having a cover-holding tenon formed integral therewith.

31. In a turbine, the combination with the vanes or buckets and a support therefor, of a discontinuous or jointed cover covering the 75 free ends of the buckets and confining the steam to the bucket spaces and means for attaching such cover to each of said buckets.

32. In a turbine, the combination with the vanes or buckets and a support therefor, of tenons made integral with the buckets and a 80 discontinuous or jointed cover confining the steam to the bucket spaces having opening through which the tenons pass, the cover being secured to the buckets by the riveting of the tenons thereon.

In witness whereof, I have hereunto set my hand this 20th day of February, 1902.

WILLIAM L. R. EMMET.
